CLAIM

The ornamental design for a mug and bowl combination, as shown and described.

DESCRIPTION

FIG. 1 is a top right perspective view of a mug and bowl combination showing my new design.

FIG. 2 is a front elevational view thereof (the rear elevational view being the mirror image of the front side).

FIG. 3 is a right side elevational view thereof.

FIG. 4 is a left side elevational view thereof.

FIG. 5 is a top plan view thereof; and,

FIG. 6 is a bottom plan view thereof.
